Primary Examiner — Lauren R Calve(74) *Attorney, Agent, or Firm* — LegalForce RAPC Worldwide**CLAIM**

(57) The ornamental design for a helmet stand, as shown and described.

DESCRIPTION

FIG. 1 is a front top right perspective view of a helmet stand showing my new design;

FIG. 2 is a front elevational view thereof;

FIG. 3 is a rear elevational view thereof;

FIG. 4 is a left side elevational view thereof, the right side elevational view being a mirror image;

FIG. 5 is a top plan view thereof; and,

FIG. 6 is a bottom plan view thereof.

The broken lines indicate unclaimed portions of the design and form no part of the claimed design.

1 Claim, 6 Drawing Sheets(56)
